UNITED STATES PATENT OFFICE.

JOHN F. MORGAL, OF SPRINGFIELD, OHIO, ASSIGNOR, BY MESNE ASSIGNMENTS, TO
BERNARD E. CRABBS.

GRINDING MACHINE.

Application filed March 7, 1921. Serial No. 450,281.

This invention relates to grinding machines and is designed more particularly for grinding articles, such as piston rings, which require grinding on two opposite sides.

The object of the invention is to provide a machine which will simultaneously grind both sides of an article; which will reduce said article to a uniform thickness with its sides in parallel planes; and further, to provide such a machine which will be semi-automatic in its operation. To this end it is a further object of the invention to provide means for operating, and controlling the movement of, two opposed grinding members; to provide means for supporting an article in position to be acted upon simultaneously by said grinding members, and for rotating said article while it is being so acted upon; and to so construct and arrange the grinding members and the support for the article that the former will automatically position the article in a plane parallel with the planes of the working faces of said grinding members. It is also an object of the invention to produce such a machine which will be of a strong durable construction and simple and positive in its operation.

In the accompanying drawings, Fig. 1 is a vertical, sectional view, taken longitudinally of a machine embodying my invention showing the mechanism in front elevation; Fig. 2 is a top, plan view of such a mechanism, partially broken away; Fig. 3 is a transverse, sectional view taken on the line $x-x$ of Fig. 1 and looking in the direction of the arrows; Fig. 4 is a sectional detail view of the spindle for one of the grinding members; Fig. 5 is a sectional view taken longitudinally of the driving shaft, showing the clutch and its controlling devices; Fig. 6 is a longitudinal, sectional view of the work-supporting chuck and its operating mechanism; Fig. 7 is a front elevation of the chuck; Fig. 8 is a detail view of a part of the controlling mechanism for the chuck; Fig. 9 is a section taken on the line 9-9 of Fig. 6; Fig. 10 is an end view of the spindle of Fig. 4; Fig. 11 is a detail view of the locking plate; Fig. 12 is a face view of the left hand coupling member of Fig. 5; and Fig. 13 is a face view of the right hand coupling member.

In these drawings I have illustrated one embodiment of my invention and have

shown the same as designed for grinding piston rings but it will be understood that the invention is applicable to machines for grinding articles of other kinds requiring a similar operation and that the changes necessary to adapt the machine to grinding of such other articles may be made without departing from the spirit of the invention.

In that embodiment of the invention here illustrated, the mechanism is mounted on a frame comprising upright members 1 which, in the present instance, are in the form of walls and constitute a housing within which a part of the mechanism is arranged. The frame also comprises a horizontal member or table 2 on which the grinding and work-supporting devices are mounted. As here shown, the table has its outer edge turned upward, as shown at 3, to form a flange or guard, which serves to prevent the fluid which flows over the work during the grinding operation from escaping about the edges of the table. The grinding mechanism proper preferably comprises two rotary grinding members, which are indicated at 4, and, in the form here shown, comprise grinding wheels of emery, carborundum or other suitable material. Preferably, these grinding wheels are so constructed as to provide a relatively narrow grinding face. To this end each wheel comprises a disk-like body 5 having a central opening and provided with an axially extending annular flange 6, the edge of which constitutes the working face of the grinding wheel. These wheels are arranged with their working faces opposed one to the other and are mounted for rotation in the same direction about coincident axes. Means are provided for separating the grinding members to permit the work to be placed in position between them and then causing them to operatively engage the work. In the present machine this is accomplished by imparting substantially equal axial movement to both grinding members but it is not necessary to move both members in order that the two members may be separated, and where both members are moved it is not essential that they should be moved equal distances. As here shown each grinding member is mounted for longitudinal reciprocatory movement, as well as for rotary movement, and to this end each grinding member is mounted upon a spindle 7 (Fig. 4), which, in turn,

is rotatably mounted in a sleeve 8, this sleeve being mounted in and held against rotation in an outer casing 9, which casing is preferably angular in cross section and is 5 mounted in suitable bearings or guides 10 carried by brackets 11 mounted on the table 2 of the main frame. The grinding member may be secured to the spindle in any suitable manner. In the present instance the 10 spindle is provided with a stud 12, screw-threaded at its outer end and extending through the opening in the disk-like portion 5 of the grinding member. Mounted on the stud 12 in the rear of the grinding member 15 and confined between the same and the body of the spindle is a gear 13 having an annular flange or bearing plate 14 which engages the outer surface of the grinding member. Arranged within the grinding member and 20 engaging the inner surface of the disk-like portion thereof is a plate 15 which is held in engagement with the disk-like portion of the grinding member by a nut 16 mounted on the screw-threaded portion of the stud 12, which nut serves to clamp the disk-like 25 portion of the grinding member firmly between the plates 14 and 15. The spindle 7 is held against longitudinal movement in its sleeve 8 and the sleeve is held normally 30 against longitudinal movement in the casing 9. Thus, while the spindle and its grinding member are free to rotate independently of the sleeve and casing they are caused to move longitudinally with these 35 members. Longitudinal movement is preferably imparted to the casing and parts carried thereby automatically and, in the present arrangement of the mechanism, these parts are moved into and held in their re- 40 tracted positions by means of a counter-weight 28 and operative movement is imparted thereto by means of a cam 17 which acts upon the end of the casing 9. As here shown the cam engages a roller 18 carried 45 by a lug or projection 19 secured to and moving with the casing. The cam may be provided with one or more working surfaces and in the type here illustrated it has two working surfaces, each of which is so 50 arranged that the first portion of the movement of the cam moves the casing 9 and, consequently, the grinding member quickly 55 toward the work. As the grinding member moves into engagement with the work its movement slows down but it is gradually 60 moved toward the work until the latter has been reduced to substantially the desired thickness and during the remainder of the movement of the cam the grinding member 65 has no longitudinal movement but serves merely to finish or smooth off the ground surface of the work. The length of the finishing operation is determined by the length of the concentric portion of the cam 70 and where a fine finish is not essential it 75 may be of very short duration, it being understood, of course, that the timing of the grinding action will be regulated according to the particular work being done. I prefer to interpose between the longitudinally mov- 80 able casing 9 and the cam an adjusting mechanism to enable the distance between the cam and the casing to be adjusted to compensate for the wear on the working face of the grinding member. I have, there- 85 fore, in the present instance, mounted the lug 19 upon a screw-threaded stud 20 which extends into the end of the casing 9, and is held against rotation therein but is capable of a longitudinal movement relatively thereto. Screw-threaded onto that portion of the stud 20 which projects beyond the end of the casing is a collar 21 having an operating handle, such as a hand wheel 22, by means of which it may be rotated. This 90 collar 21 bears against the end of the casing and it will be apparent that any rotation thereof will move the stud 20 relatively to the casing and increase or decrease the distance between the end of the casing and the 95 axis of the cam. The collar is provided with a fine scale whereby very exact adjustments may be made. Further, suitable means are provided to prevent accidental interference with this adjustment and this device is here 100 shown as a serrated plate 23 adjustably mounted in a groove 24 in the collar, in frictional engagement with the teeth of the stud to resist the movement of the collar relatively to the stud. In addition to the device 105 for making fine adjustments of the grinding wheel it is desirable that means should be provided for making longer adjustments and, to this end, the sleeve 8 is provided with a rib 25 having therein a series of 110 notches or recesses 26 arranged at fixed intervals and each adapted to receive the end of a screw 27 mounted in the casing 9. By engaging this screw with different notches or recesses the sleeve may be secured in different longitudinal positions relatively to the casing. After this longer adjustment 115 has been secured the exact or finer adjustment may be secured by means of the collar 21 and stud 20. While I have described but 120 one grinding member and the manner of supporting and operating the same, it will be understood that the two grinding members are identical and that the description of the one applies equally to the other. Further, it will be understood that the cams 125 17 for the two grinding members are so arranged that the operative movement of the grinding members will be simultaneous. Thus, it will be apparent that the two grinding members are moved toward one another until the distance between them is equal to the thickness the work is to have when the grinding operation is completed. When the grinding members have been moved into 130

these positions the continued movement of the cams will bring the recesses thereof into alignment with the rollers 18 and the counterweights will move the respective grinding members quickly to their retracted positions, thus separating the same to permit of the removal of the work which has been completed and the insertion of another article to be ground.

10 A suitable work-supporting device is provided for supporting the work in a position to be simultaneously engorged by the two grinding members and this supporting device is preferably of such a character that it will permit the work to have axial movement, thereby enabling the same to be moved into its correct position by the grinding members as the latter contact therewith. This floating support is, however, of such 15 a character that it will cause the work to rotate while it is in engagement with the grinding member. Where the articles to be ground are hollow, as is the case with the piston rings for which the present machine 20 is chiefly designed, I prefer to use a chuck, such as is herein illustrated. The work holding device as a whole, which is illustrated in Figs. 6 to 9, comprises a hollow shaft 29 journaled in a suitable bearing bracket 30 on the table 2. Mounted on one end of this hollow shaft 29 is a chuck which, in the form here shown, consists of a head 31 screw-threaded onto a stud 32 which is rigidly secured to and preferably formed integral with the shaft 29. The head 31 is 25 provided with a plurality of radial guide-ways, in the present instance, five, in which are mounted a corresponding plurality of fingers 33 capable of radial movement and 30 each provided with a projection or pin 34 which extends through a radial slot 35 in the head to control the radial movement of the respective fingers. Extending about the 35 several pins 34 is a resilient member 36, such as a rubber band or spring, which tends to move the several fingers 33 inward. Slidably mounted within the hollow shaft and extending through the head 31 of the chuck 40 is an operating rod 37 having a tapered end or head 38 arranged centrally of the chuck 45 head and engaging the inner ends of the several fingers 33, these ends being beveled to fit the tapered surface of the end of the operating rod. It will be apparent that this 50 construction is such that the fingers 33 of the chuck will be held normally in their retracted positions but that longitudinal movement of the operating rod 37 will move the fingers outward against the tension of the 55 spring or retracting member 36, thereby forcing the outer ends of the fingers into engagement with the inner surface of the hollow work, or piston ring. The outer ends of the fingers are provided with portions adapted to grip the surface of the work to cause 60 it rotate with the chuck. In the present instance the outer ends of the fingers are beveled rearwardly so as to provide the forward portions thereof with edges which will bite into the work and hold the same against 65 rearward rotation relatively to the chuck. Further, it will be noted that the fingers are capable of independent movement so that they will accommodate themselves to irregularities in the inner surface of the work. It 70 will also be noted that inasmuch as the contacting portions of the chuck fingers are in the nature of thin edges they will offer little resistance to the movement of the work axially of the chuck. Consequently, it is not 75 necessary that the work should be placed on the chuck with exactness because the grinding members themselves will move the work into proper position. The rotary shaft 29 for the chuck is driven by means of a driving member or gear 39 which is rigidly secured thereto at that end opposite the chuck head and a spring 40 is coiled about the end of the operating rod, which projects beyond 80 that end of the shaft remote from the chuck 85 head, and is confined between the end of the shaft and a collar 41 secured to the end of the operating rod. This spring serves to move the tapered head of the operating rod into operative engagement with the fingers 90 and to maintain a constant pressure on the fingers, which pressure tends to hold them in engagement with the work. To release the fingers from the work, to permit the removal of the latter, the rod is moved longitudinally 95 against the tension of the spring 40, this being accomplished by means of a foot lever 42, Fig. 3, pivotally mounted on the frame near the bottom thereof and connected by means of a rod 43 with a crank arm 44, Fig. 100 6, rigidly secured to a rockshaft 45, Fig. 8, rotatably mounted near the end of the operating rod 37 and having a finger or projection 46 adapted to enter a transverse slot 47 in a rod 137 reciprocally mounted in bearing 138 and having at one end an arm 139 arranged to engage and actuate the operating rod 37. Thus the pressure of the foot on the 105 foot lever 42 will rock the shaft 45 and thereby impart longitudinal movement to the operating rod against the tension of the spring 40, thus moving the tapered head of the rod away from the fingers and permitting the latter to be moved inward and out of engagement with the work by means of the retracting member 36. To facilitate the placing of the work on the chuck I prefer to provide the same with a guide or stop member which is in the form of a spider 48, Figs. 6 and 7, 110 having in the present instance, three arms 49 radiating from the axis of the shaft 29 and each provided with a roller 50. This spider is arranged in the rear of the chuck fingers 33 and in such a position that it will form a 115 stop to limit the movement of the work as 120 125 130

the latter is placed over the fingers. Thus, when a piston ring is being placed upon the chuck it is simply placed about the fingers and moved into engagement with the rollers 50 and the foot lever released to permit the chuck fingers to engage the inner surface of the ring. As has been explained no further adjustment is necessary as this will be accomplished by the grinding members. It is only necessary that a guide should be provided of such a character that it will facilitate the placing of the work in a position to be engaged by the fingers. The rollers permit the work to rotate freely relatively to the spider or guide but ordinarily the positioning of the work by the grinding members will move the same out of engagement with these rollers.

One chuck and one guide or spider will take care of work of different diameters but it is not desirable that the chuck fingers should have a range of movement sufficient to take care of any wide variation in diameters. It is preferable that separate chucks should be used. Likewise, while the length of the rollers 50 of the spider is such that they will accommodate work of different diameters it is preferable that the spider should be removed and one of different size substituted where the work varies materially in diameter. The spider is adjustable toward and away from the chuck fingers to accommodate it to the varying thickness of the work and, as here shown, the three arms 49 are separately mounted by providing each with a base 51 which is slidably mounted in a groove 52 of the bracket carrying the chuck. To lock the arms in adjusted positions each base is provided with a longitudinal groove 55 into which extends one edge of a disk 54, the other edge of which extends into a socket 155 where it may be engaged by the head of a screw 56, thus clamping the spider firmly in position.

The several parts of the mechanism may be driven in any suitable manner and from any suitable source of power but I prefer to drive the several parts of the mechanism from a single source of power and to distribute the power and reduce the speed of movement as may be necessary. To this end I have mounted on the table 2 an electric motor 57 of sufficient power to drive the complete mechanism. This motor is directly connected with a main driving shaft 58 mounted at its ends in suitable bearings 59 and having its intermediate portion in the form of a drum 60 about which extend two endless driving members. In the present instance, the drum is provided with gear teeth extending for substantially the full length thereof and, with the flexible driving members, which are shown at 61, comprises what is known as a noiseless chain drive. These flexible driving members extend about the gears 13 which, as above explained, are secured to the spindles for the grinding members and thus these spindles are driven at a very high rate of speed. Extending about one end of the toothed drum or gear 60 is a second flexible driving member 62, Fig. 3 of similar character, which extends about a gear 63 rotatably mounted on a bracket 64 secured to the underside of the table 2. Secured to the gear 63 is a smaller gear 65 from which, by means of a flexible drive 66, the power is transmitted at a reduced speed to a gear 67 which is mounted on a longitudinal shaft 68 journaled in bearings 69 in the end members of the frame and in an intermediate bracket 70. This shaft 68 projects beyond the end members of the frame and is provided with suitable worms 71 Fig. 5 meshing with worm gears 72 rigidly secured to the lower ends of vertical shafts 73, to the upper ends of which are secured the cams 17. The gear 67 is loosely mounted on the shaft 68 and is adapted to be connected thereto by means of suitable clutch mechanism. As here shown the gear 67 is provided on one face with a clutch member 74 Fig. 5 adapted to cooperate with a clutch member 75 rigidly secured to the shaft. Springs 76 confined between collars 77 and 78 secured to the shaft and to the gear, respectively, serve to hold the clutch members normally in operative engagement. Preferably, the collar 78 is connected with the gear for longitudinal movement only and not for rotary movement and, to this end, a bearing, preferably a ball bearing, 79, is interposed between the collar and the gear. I prefer to utilize cooperating cams to impart longitudinal movement to the gear 67 and thus separate the clutch members. To this end I have mounted on the shaft 68 two cam members 80 and 81, both being so connected with the shaft that they are free to rotate thereon and the cam 80 being held against longitudinal movement on the shaft. Slidably mounted in the hub of the clutch member 75 are a series of pins 82 which are so connected with the cam member 81 that any longitudinal movement of that member will be imparted to the pins, and through the medium of the pins to gear 67 and clutch member 74. Preferably, a bearing, such as a roller bearing 83, is interposed between the pins and the cam member 81 so that the rotary movement of the pins with the clutch member 75 will not affect the cam member 81. The cam member 81 is provided with an arm 84 which is secured at its outer end to a fixed support, such as one of the vertical members of the frame so that this cam is held against rotary movement but is free to move axially of the shaft. The cam member 80 also has an arm or lever 85 which is connected at its outer end with the rod 43 leading to the foot lever 42. Thus, when

the foot lever is operated the cam 80 will rotate and because of the cooperating faces of the cams 80 and 81 longitudinal movement will be imparted to the later and thence 5 through the pins 82 to the gear 67, thus separating the clutch members and interrupting the movement of the shaft 68. The connections between the rod 43 and the cam 80 and the operating rod for the chuck are 10 so arranged that when the foot lever is depressed the clutch members on the shaft 68 will first be separated and then the operating rod actuated to retract the fingers of the chuck and, vice versa, when the foot lever 15 is released and allowed to return to its normal position under the action of the spring 86, the fingers of the chuck will engage the work before the clutch members come into engagement. This is important because the 20 shaft 29 of the chuck is driven from the shaft 68 and rotary movement imparted to the chuck while the fingers were retracted would result in the work being thrown off of the same. The driving connection between the shaft 68 and the chuck comprises 25 a flexible driving member 87 Fig. 3 extending about a gear 88 on the shaft 68 and about a gear 89 on a countershaft 90. Connected with this latter gear is another gear 30 91 which is connected by a flexible drive 92 with the gear 39 on the shaft 29.

In order that the cams 17 may be adjusted relatively one to the other to cause them to move in proper timed relation I prefer to 35 form the shaft 68 in two parts and to connect these parts by a coupling consisting of disks 94 and 95 Fig. 5 each rigidly secured to one portion of the shaft 68. Each disk has a series of openings 96 formed near the 40 edge thereof and arranged concentrically to the axis thereof. The openings of each series are spaced the same distance apart but the openings of the two series are spaced different distances apart. These openings 45 are adapted to receive a pin 97 or other connecting device and, in the present instance, the openings are in the form of recesses formed in the inner face of the disk and extend but part way through the disk. By 50 shifting one of the disks about its axis it can be moved through a series of short steps relatively to the other disk and at the end of each step of its movement some one of the recesses therein will register with one of the 55 recesses in the other disk, thus enabling a very fine adjustment of the two parts of the shaft to be secured and this adjustment of the shaft likewise adjusts the cams. The two disks are rigidly connected one to the 60 other by means of bolts 98 and, in order that further adjustment may be had, one of the disks, in the present instance the disk 95, is provided with concentric slots 99 through which the bolts extend.

65 It is usually desirable that grinding of this

kind should be done in the presence of a fluid and, in the present instance, I have provided means for causing such a fluid to flow over the work while the grinding members are acting thereon. This fluid is usually water to which has been added a substance to prevent rusting and it is contained in a receptacle 100 Fig. 1 within the housing formed by the side walls 1 of the frame. A pump 101, which may be of any suitable 70 character, such as a small rotary or gear pump, is connected with the receptacle by means of a pipe 102 and has connected therewith a discharge pipe 103 which leads to a point above the work and discharges directly onto the same. The fluid falls from the work onto the table 2 which is provided with a drain pipe 104 to return the same to the receptacle 100. The pump 101 may be driven in any suitable manner but preferably it is driven by a flexible driving member or chain 105 passing about a sprocket wheel 106 on the shaft 68 and about a second sprocket wheel 107 which is connected 75 with the pump.

In the operation of grinding wheels of this character the cutting faces of the wheels often become glazed so as to reduce their cutting qualities and increase the tendency to heat. To correct this condition the face of the wheel must be dressed off by the use of a suitable implement. To enable this dressing process to be accomplished quickly and easily I have provided a dressing implement which is mounted so that it can be brought quickly into operative relation with the two wheels and will dress both working faces at the same time. Preferably, the implement is mounted upon a cover plate or guard 108 which extends over the grinding 80 wheels. The implement itself consists of a support or guide bar 109 slidably mounted in a bracket 110 which is rigidly secured to the guard plate and has at its lower end a cross-head or bar 111 provided at its ends with suitable devices for dressing the faces of the wheels, such, for example, as diamonds, as 85 shown at 112. The guide bar 109 is mounted centrally with relation to the two grinding wheels and the cross head 111 is of such a length that when the two grinding members are in their separated positions the implement may be placed between them and the dressing devices 112 will act simultaneously 90 upon the faces of the two wheels. To permit of the cross-head being brought into operative relation with the grinding wheel the guide bar 109 is provided with teeth, as 95 shown at 113, which mesh with a pinion 114 to which is connected an operating handle or wheel 115. A thumb screw 116 serves to lock the device in its operative or inoperative 100 position.

105 The operation of the device will be readily understood from the foregoing description.

and it will be apparent that the operator has but to depress the foot lever, place a ring in position on the chuck and release the foot lever to cause the grinding members to operatively engage the ring, center the same and grind it to the desired thickness. As soon as the grinding operation is completed the grinding members are retracted to their separated positions and when the grinding members are so retracted the operator again depresses the foot lever, thus interrupting the operation of the parts, releasing the finished ring and permitting the same to be removed, an unfinished ring substituted therefor and the operation repeated. In the present type of machine the cam makes approximately four revolutions per minute and inasmuch as the rings can be changed very rapidly and two operative movements are imparted to the grinding members for each revolution of the cam it will be apparent that several rings per minute can be ground. Further, it will be apparent that the operation of the machine is exceedingly simple and that the machine does not require any large degree of skill for its operation. Further, the parts are of such a character that they are strong and durable and will not be easily disarranged or broken. The means which is provided for adjusting the grinding members enables the entire operative portion of the same to be utilized.

While I have shown and described one embodiment of my invention it will be understood that this has been chosen for the purposes of illustration only and that I do not desire to be limited to the details of construction shown and described, for obvious modifications will occur to a person skilled in the art. Further, it will be understood that while the grinding members of the present machine are so arranged that the opposite sides of the finished work are in parallel planes, this is not an essential part of the invention, but that the invention, either as a whole, or in part, may be embodied in machines designed for grinding various articles which require grinding on two sides.

Having thus fully described my invention, what I claim as new and desire to secure by Letters Patent, is:—

1. In a grinding machine, two grinding members mounted for rotation about a common axis and having opposed grinding faces, means for rotating said grinding members, means for moving one of said grinding members axially toward and from the other grinding member, a work support mounted for rotation about an axis substantially parallel with the axis of said grinding members and having means for supporting an article to be ground for rotation about the axis thereof, a portion of said article extending between said grinding members so that the lateral faces of said

article will be simultaneously acted upon by the respective grinding members, said supporting means being of such a character that said article will be automatically positioned thereon by its contact with said grinding members, and means for rotating said work support during the grinding operation to cause the entire circumferential portion of said article to pass between said grinding members. 75

2. In a grinding machine, two grinding members mounted for rotation about a common axis and having opposed grinding faces, means for rotating said grinding members, means for moving one of said grinding members axially toward and from the other grinding member, a work support mounted for rotation about an axis substantially parallel with the axis of said grinding members and having means for supporting an article to be ground for rotation about the axis thereof, a portion of said article extending between said grinding members so that the lateral faces of said article will be simultaneously acted upon by the respective grinding members, said supporting means being movable into and out of operative position with relation to said article, guides to initially position said article with relation to said supporting means when the latter is in an inoperative position, said article being supported for axial movement with relation to said supporting means to permit it to be finally positioned by contact with said grinding members, and means for rotating said work support during the grinding operation to cause the entire circumferential portion of said article to pass between said grinding members. 85 90 95 100 105

3. In a grinding machine, two grinding members mounted on separate spindles which are separately mounted for rotation about a common axis and for axial movement, means acting on said spindles to normally hold said grinding members in separated positions, cams acting on said spindles to move said grinding members one toward the other, a two part shaft the two parts of which are connected with the respective cams, means for adjustably connecting the two parts of said shaft one to the other, means for rotating said shaft as a unit, and a rotatable work support mounted adjacent to said grinding members and arranged to support the work between the same to cause it to be acted upon simultaneously by both of said grinding members. 110 115 120

4. In a grinding machine, two grinding members rotatable about a common axis and movable toward and from each other, cams acting on the respective grinding members to impart axial movement thereto, a two part shaft the two parts of which are connected with the respective cams, means for 125 130 135

- adjustably connecting the two parts of said shaft one to the other, and a rotatable work support mounted adjacent to said grinding members and arranged to support the work between the same to cause it to be acted upon simultaneously by both of said grinding members.
5. In a grinding machine, two grinding members rotatable about a common axis and movable toward and from each other, a rotatable work support mounted adjacent to said grinding members, and having means to support an annular member between said grinding members, said means being of such a character that it will cause said annular member to rotate with said support, but will permit it to move axially thereof when engaged by one of said grinding members.
6. In a grinding machine, two grinding members rotatable about a common axis and movable toward and from each other, a work support to support an article to be ground between said grinding members, means to automatically move said grinding members simultaneously, into engagement with said article, and means under the control of the operator to interrupt said movement of said grinding members without interrupting the operation of said machine as a whole.
7. In a grinding machine, two rotatable grinding members, means to move said members toward and from each other, a work support having means to engage the work and support the same while it is being ground, means to rotate said work support, and means to interrupt the rotation of said work support independently of the operation of said grinding members.
8. In a grinding machine, two rotatable grinding members, means to move said members toward and away from each other, a work support having means to engage the work and support the same while it is being ground, means to rotate said work support, and a single device under the control of the operator for first interrupting the movement of said grinding members relatively to each other and the rotation of said work support and then to release said work from said work support.
9. In a machine for grinding rings, two grinding members rotatable about a common axis and capable of axial movement toward and away from each other, a work support comprising a head adapted to enter a ring and having radial fingers to engage the inner surface of said ring and support the same between said grinding members, and means for rotating said head and for imparting axial movement to said grinding members.
10. In a grinding machine, two grinding members, separate spindles for the respective grinding members, a bearing for each
- spindle, means to slidably support said bearings, whereby said grinding members may rotate relatively to the respective bearings and may be moved axially therewith, and means for automatically and simultaneously imparting axial movement to said supporting means.
11. In a grinding machine, a grinding member, a spindle therefor, a bearing sleeve in which said spindle is rotatably mounted, a slidable casing, means for securing said sleeve in said casing, and means for imparting longitudinal movement to said casing.
12. In a grinding machine, a grinding member, a spindle therefor, a slidable casing, means for rotatably supporting said spindle in said casing, a cam, and a part connected with said casing whereby said cam may impart longitudinal movement to said casing, and means for varying the distance between the axis of said cam and said casing to compensate for the wearing away of said grinding member.
13. In a grinding machine, a bearing, a casing slidably mounted in said bearing and held against rotation therein, a bearing sleeve mounted in said casing and held against movement relatively thereto, a spindle journaled in said bearing sleeve, a grinding member carried by said spindle, a cam, and a part carried by said casing and arranged to be acted upon by said cam to impart longitudinal movement to said casing and said grinding member.
14. In a grinding machine, a bearing, a casing slidably mounted in said bearing and held against rotation therein, a bearing sleeve mounted in said casing and held against rotation relatively thereto, a spindle journaled in said bearing sleeve, a grinding member carried by said spindle, a cam, a stud carried by said casing and having a part arranged to be engaged by said cam, and means for adjusting said stud relatively to said casing to compensate for the wear of said grinding member.
15. In a grinding machine, a bearing, a casing slidably mounted in said bearing and having rotation therein, a bearing sleeve adjustably mounted in said casing and held against rotation relatively thereto, a spindle journaled in said sleeve, a grinding member carried by said spindle, a cam, a stud adjustably mounted on said casing, and a part carried by said stud and arranged to be engaged by said cam to impart longitudinal movement to said casing and said grinding member.
16. In a grinding machine, a bearing, a casing slidably mounted in said bearing and having rotation therein, a bearing sleeve adjustably mounted in said casing and held against rotation relatively thereto, a spindle journaled in said sleeve, a grinding member carried by said spindle, a cam, a stud ad-

- justably mounted on said casing, a part carried by said stud and arranged to be engaged by said cam to impart longitudinal movement to said casing and said grinding member, said stud being held against rotation relatively to said casing and having a screw-threaded portion extending beyond the end of said casing, and a collar screw-threaded onto said stud and bearing against the end of said casing.
17. In a grinding machine, a bearing, a casing slidably mounted in said bearing and held against rotation therein, a bearing sleeve adjustably mounted in said casing and held against rotation relatively thereto, a spindle journaled in said sleeve, a grinding member carried by said spindle, a cam, a stud adjustably mounted on said casing, a part carried by said stud and arranged to be engaged by said cam to impart longitudinal movement to said casing and said grinding member, said stud being held against rotation relatively to said casing and having a screw-threaded portion extending beyond the end of said casing, a collar screw-threaded onto said stud and bearing against the end of said casing, and means for preventing the accidental movement of said collar on said stud.
18. In a grinding machine, two rotatable grinding members movable toward and from each other, means for moving said members toward each other, a rotatable work holder for supporting the work between said grinding members, a shaft, operative connections between said shaft and said work holder and between said shaft and said means for moving said grinding members, a driving member for said shaft, a clutch connection between said driving member and said shaft, and means for actuating said clutch.
19. In a grinding machine, two rotatable grinding members movable toward and from each other, cams for moving said members toward each other, a rotatable work holder for supporting the work between said grinding members comprising an operable part to retain the work thereon, a shaft, operative connections between said shaft and said work holder and between said shaft and said cams, a driving member for said shaft, a clutch connection between said driving member and said shaft, and a device for interrupting said clutch connection and operating said work holder to release the work.
20. In a grinding machine, two rotatable grinding members movable toward and
- away from each other, cams for moving said members toward each other, a rotatable work holder for supporting the work between said grinding members comprising an operable part to retain the work thereon, a shaft, operative connections between said shaft and said work holder and between said shaft and said cams, a driving member for said shaft, a clutch connection between said driving member and said shaft, and a foot lever for interrupting said clutch connection and operating said work holder to release the work.
21. In a grinding machine, the combination, with two rotatable grinding members movable toward and away from each other, cams for moving said members toward each other, a rotatable work holder for supporting the work between said grinding members comprising an operable part to retain the work thereon, means for rotating said work holder, and a single device under the control of the operator for interrupting the rotation of said work holder and the movements of said cams and for manipulating said work holder to release the work thereon.
22. In a grinding machine, two rotatable grinding members mounted for axial movement, cams to act upon the respective members to move them toward each other, a two part shaft operatively connected with said cams, and means for adjusting the two parts of said shaft relatively one to the other to adjust said cams relatively one to the other, and a work holder to support the work between said grinding members.
23. In a grinding machine, two rotatable grinding members mounted for axial movement, cams to act upon the respective members to move them toward each other, a two part shaft having its two portions connected with the respective cams, coupling members secured to the adjacent ends of the respective shafts, said coupling members each having a concentric series of openings, the openings in one member being spaced apart a greater distance than the openings in the other member, whereby the rotary adjustment of said coupling members will bring different openings into alinement, a connecting device adapted to enter the two openings which are in alinement, means to prevent further relative movement of said members, and means for connecting the two members of said coupling one to the other.

In testimony whereof, I affix my signature hereto.

JOHN F. MORGAL.
